DESIGN FOR A SHOE HEEL

Arthur Greenbaum, Beachmont, Mass., assignor to Panther-Panco Rubber Co. Inc., Chelsea,
Mass., a corporation of Massachusetts

Application November 20, 1936, Serial No. 66,039

Term of patent 14 years

To all whom it may concern:—

Be it known that I, Arthur Greenbaum, a citizen of the United States, residing at Beachmont, in the county of Suffolk and Commonwealth of Massachusetts, have invented a new, original, and ornamental Design for a Shoe Heel, of which the following is a specification, reference being had to the accompanying drawing, forming a part thereof.

In the drawing, Fig. 1 is a plan view of a shoe heel showing my new design; and Fig. 2 is a cross-section on the line 2—2 of Fig. 1.

I claim:

The ornamental design for a shoe heel substantially as shown.

ARTHUR GREENBAUM.
